UNITED STATES PATENT OFFICE.

WALTER A. KEITH, OF LOS ANGELES, CALIFORNIA, ASSIGNOR TO THE CHICAGO LUBRICATOR COMPANY, OF CHICAGO, ILLINOIS, A CORPORATION OF ILLINOIS.

LUBRICATING SYSTEM.

1,008,828.

Specification of Letters Patent. Patented Nov. 14, 1911.

Application filed January 2, 1909. Serial No. 470,409.

To all whom it may concern:

Be it known that I, WALTER A. KEITH, a citizen of the United States, residing at Los Angeles, in the county of Los Angeles and State of California, have invented new and useful Improvements in Lubricating Systems, of which the following is a specification.

My invention relates more particularly to means to properly lubricate the flanges on the wheels of railway rolling stock and the rails on which they travel.

It is one of the objects of my invention to provide an apparatus easily accessible to the engineer and under his control, for properly lubricating the wheel flanges and the rails on the curves in the track wherever required.

The invention consists in a lubricant supplying medium, exposed to air pressure, which conducts the lubricant to a distributing nozzle where it is atomized and forcibly discharged upon the wheel flange and rail, to thereby reduce friction and wear.

My invention is shown in the accompanying drawings, in which—

Figure 1 is an elevation of a locomotive engine with my lubricating system in place thereon. Fig. 2 is a side view partly in section of the valve mechanism for spraying the atomized oil. Fig. 3 is a view partly in section of the strainer. Fig. 4 is a top plan view of the spraying nozzle. Fig. 5 is an elevation, on a larger scale, and looking toward the rear, of portions of the front of the locomotive with the lubricating system in place. Fig. 6 is a side view of portions of the front end of the tender with a modified form of my system placed thereon. Fig. 7 is a rear elevation of the parts shown in Fig. 6. Fig. 8 is a plan view of the adjusting bar and adjusting rod and connecting mechanism of the modification shown in Figs. 6 and 7. Figs. 9 and 10 are details of the modified construction.

Referring to Fig. 1, 11 represents the lubricating oil tank, which is filled through the filling pipe 12. This tank is connected with the compressed air reservoir (not shown) by the air supply pipe 13. This pipe has an offset 14 through which the air pressure is maintained in the tank, and the supply of lubricant fed therefrom is always

under the control of the engineer by means of the pressure regulating valve 41 (see Fig. 55 1) in the cab of the engine. This valve may be of such character as to indicate to the engineer any failure to use the lubricant at the proper places and in proper quantities, so that the excuse that the device is not 60 working properly will not be available. The air pipe 13 extends downwardly and communicates with the spray valve 15. There being a spray valve on each side of the truck to properly spray the head of each 65 rail and the flange of each wheel thereon, and to that end I have connected this air supply pipe 13 with the horizontally disposed pipe 39 which connects at each end with a spray valve 15 having a spray nozzle 70 24. This is more particularly shown in Fig. 7. The downwardly extending oil supply pipe 17 is also connected with horizontally disposed pipe 40 which also terminates at each end in the spray valves. Disposed on 75 the oil supply pipe 17 intermediate the oil tank and the spray valve is the strainer 16 shown in enlarged detail in Fig. 3. When pressure is put on, the air in the air pipe will cause the oil in the oil tank to flow 80 down through the pipe 17 into the spray valve 15 and the air passing into the spray valve through the air pipe 13 will cause the same to be ejected in the form of a spray, as shown at 18 in Figs. 2 and 4. The manner in which the oil is atomized and caused to be issued into a spray is plainly illustrated in Fig. 2. For the purpose of keeping the oil in proper condition to be sprayed and to prevent it from clogging in the spray 85 valve in case of change of temperature; I have provided a chamber 19 in the top of the spray valve with a steam pipe 20 which communicates with the exhaust of the air pump 20'. Leading out of this chamber are 90 a plurality of discharge ports 21 so that the exhaust steam may pass out through these exhaust ports in the shape of steam and water and keep the spray valve at a proper temperature. The nozzle of the spray valve 100 is located in proper position to eject the atomized oil against the inner edge of the wheel flange 22, shown in dotted lines in Fig. 4.

In Figs. 6 and 7 I have shown an oil tank, 105 mounted on the front end of the locomotive

tender, connected with the spraying mechanism and adapted to project a spray of atomized oil on the flange of the wheel and the head of the rail 23, Fig. 7, the spray nozzle 24 being prolonged downwardly so as to discharge the spray at the proper position to oil the flange and the rail. The oil tank located on the tender, is connected with the spray valve and the air supply in manner similar to that on the locomotive already described, except that the connections on the tank have flexible hose unions 24' to permit a lateral movement of the spray nozzles relative to the frame of the truck as the truck is passing over curves in the track. This lateral movement of the spray nozzles relative to the truck is accomplished by the adjusting bar 26, which has an intermittent longitudinal movement on the frame 27. At each end of the bar 26 a bolt 28 projects downwardly through longitudinal slots 29 therein and has a screwthreaded engagement in the frame 27, thereby permitting the adjusting bar to have the aforesaid longitudinal movement on the frame 27. To hold the bar in its normal adjusted position on the frame, coiled springs 30 are connected at one end by the bolts 28 to the frame and at the other end are secured by the bolts 31 to the adjusting bar. This adjusting bar is provided with recesses 32 for the reception of the flanges 33 on the wheels, so that it is kept at all times in the same point with reference to the flanges on the wheels. In rounding curves on the track these flanges on the wheels have a movement independent of the frame 27 of the truck, and the flanges on the wheels will always govern the relative position of the adjusting bar. Now, if no provision were made to adjust the discharge nozzle of the spraying valve, the nozzle would be moved toward and away from the rail and the flange of the wheel in rounding curves, but means are herein provided to keep the discharge nozzle of each spray valve in its proper position with reference to the flange of the wheel and the head of the rail, so that the atomized oil ejected in the form of a spray from the nozzle will always spray the flange and the rail as follows. A pin 34 is rigidly secured to the bottom of the frame and projects downwardly beyond an adjusting rod 35, which has an offset portion 36 which partly surrounds the downwardly projecting pin 34 at this point, so that said rod will be moved longitudinally, by virtue of its connection with the fixed downwardly projecting pin, as the truck swings. The adjusting rod 35 is pivotally connected at both of its ends, as at 37, with projecting arms 38 rigidly secured to the nozzles 24 of the spray valves, so that the nozzles will be rotated slightly when the adjusting rod moves, and the discharge nozzles always will be kept close to the flanges

and the rails, the flexible connections 25 permitting this limited movement.

Having described my invention, what I claim as new and desire to secure by Letters Patent is:—

1. In a lubricating system, for railway rolling stock, means to distribute the lubricant on the wheel flange and the rail, comprising an oil tank in communication with an air supply under pressure having an air-regulating valve thereon, a discharge pipe extending from the oil tank, a spray valve connected with said oil discharge pipe, a pipe connecting the spray valve with the air supply, and a nozzle extending from the spray valve and adapted to spray the lubricant on the wheel flange and the rail. 70

2. In a lubricating system, for railway rolling stock, means to spray the lubricant, comprising an oil tank under air pressure, a discharge pipe leading therefrom, a spray valve connected with said oil-discharge pipe, a spray nozzle on said valve adapted to project a spray of oil, and an air pipe communicating with the tank and the valve, combined with means to shift the nozzle when rounding curves. 85

3. In a lubricating system in communication with an air pressure supply provided with means to properly eject a lubricant in the form of a spray, the herein described means to direct the spray on rounding curves in the track, comprising a shifting bar mounted on the frame of a wheeled vehicle and having a longitudinal movement thereon, the said bar having mounted on either end thereof a spiral spring to control the longitudinal movement of the shifting bar, and spraying nozzles workably mounted on said shifting bar, the said shifting bar having recesses therein for the engagement of the flanges of the wheel, combined with a wheeled vehicle. 95

4. A lubricating system adapted to the use of air in ejecting a lubricant on the flange of the wheel and on the rail, comprising an oil tank in communication with air under pressure, means to regulate the pressure thereon, a discharge pipe leading from the bottom of said tank to a spray valve, a spray valve secured to the said pipe and connected directly with the air supply for the oil tank, said valve having a discharge nozzle adapted to project a spray of air and oil on the flange of the wheel and on the rail, and means to maintain the nozzle of the valve at a uniform distance from the flange of the wheel when the wheel is passing around curves on the track. 110

5. A lubricating system for railway cars adapted for the use of air under pressure to distribute the lubricant externally of said system, comprising an air pipe communicating with air under pressure, an air regulating valve thereon, an oil tank, and a spray 125

130

valve, said oil tank having connection with the air pipe and having a discharge pipe leading therefrom to the spray valve, and a separate air supply pipe opening into the spray valve so that said spray valve is in communication with the air under pressure and with the oil tank.

6. A lubricating system for railways, comprising an oil supply tank, a spray valve, a source of air under pressure communicating with said tank and said valve, a steam chamber in said valve, a steam pipe communicating therewith, and exhaust ports leading from said chamber.

7. A lubricating system for flanged wheels comprising a spray valve in the proximity of the wheel flange, an oil supply operatively connected with said spray valve, means for introducing fluid under pressure in said spray valve, and means for leading steam to a chamber located on said spray valve.

8. A lubrication system for lubricating the flanges of wheels, comprising an atomizer head, an oil supply connected with said atomizer head, means for supplying a fluid under pressure to said oil supply and to said atomizer head, a steam chamber operatively connected with said atomizer head, said steam chamber being provided with discharge ports, and means for supplying steam to said steam chamber.

9. A system for lubrication of the flanges

of wheels, comprising a spray valve which includes a nozzle connected with an air supply, a casing provided with an oil chamber 35 surrounding said nozzle, said casing also being provided with a steam chamber, means for conducting steam to said steam chamber, means for conducting oil to said oil chamber, and a head in said casing provided with an 40 opening in axial alinement with the opening in said nozzle, said head being arranged in close proximity to the flange of the wheel to be lubricated.

10. A lubricating system, comprising an 45 oil tank, an air supply, a spray nozzle, means connecting the air supply with the oil tank and delivering air pressure to the top of the oil in the tank and a separate connection for conveying the oil by gravity from the 50 tank to the spray nozzle and which is exposed to the pressure of the air in the tank, and an independent connection for supplying air to the spray nozzle, the supply of air pressure to the tank and to the spray nozzle 55 being uninterrupted during the operation of the system.

In witness that I claim the foregoing I have hereunto subscribed my name this 23rd day of December, 1908.
